UNITED STATES PATENT OFFICE.

AUGUST SUNDH, OF HASTINGS-UPON-HUDSON, NEW YORK.

ILLUMINATING DEVICE.

1,136,378.

Specification of Letters Patent.

Patented Apr. 20, 1915.

Application filed November 13, 1914. Serial No. 871,889.

To all whom it may concern:

Be it known that I, AUGUST SUNDH, a citizen of the United States, residing in Hastings-upon-Hudson, in the county of 5 Westchester and State of New York, have invented a new and useful Improvement in Illuminating Devices, of which the following is a specification.

My invention relates to door knob lights, 10 and is more particularly directed to a device for illuminating a key hole or safe dial or other objects of a similar nature.

One object of the invention is the provision of means contained within a door 15 knob or the knob of a safe dial for effecting the desired illumination.

Another object is the provision of a knob in which is contained a small electric lamp and a suitable source of electric energy for 20 lighting the lamp.

Another object of the invention is the provision of an electric battery and a miniature lamp together with a push button or other device for closing a circuit between 25 the battery and lamp and a reflector for directing the light to the desired place, the whole being contained within the knob structure and thus guarded against injury from an external source.

30 A further object of the invention consists in providing a source of illumination which may be controlled at will and is contained within a knob, handle or analogous device, the arrangement being such that all of the 35 parts are immediately accessible for inspection, repair or replacement.

Other objects of the invention will appear hereinafter, the novel combinations of 40 elements being pointed out in the appended claims.

Figure 1 is a sectional view of my invention; Fig. 2 is a fragmentary end view of Fig. 1; Figs. 3 and 4 illustrate my invention applied to a safe and to a door.

45 Similar parts are designated by like reference characters throughout all of the figures.

It is well known that oftentimes one experiences the greatest difficulty in locating a 50 keyhole after dark, and even in the day time the same difficulty may be present should the key hole be located where the light is feeble, as so often is the case. The usual way to find the keyhole when the light is insufficient is to strike a match, if one can be 55 found, and after locating the keyhole, throw

the match, still lighted, into a corner. This practice is at best not only a nuisance, but also dangerous, since a carelessly thrown lighted match may very easily be the cause 60 of a serious fire. When it is desired to manipulate the dial of the combination lock of a safe, if the light be poor it is almost impossible to see the numbers on the dial, and even though the natural light be good or an 65 artificial light be used, the placing of the hand on the dial knob is sure to cast a shadow on the dial, which obviously renders it difficult to work the combination.

By reason of my invention I am enabled 70 to provide a simple, practical and efficient means for lighting a keyhole or the dial of a safe. The lighting device, being contained within the knob does not require any additional space, and will not cast any shadows. 75 The first cost is very moderate, and, since it is intended that the light be used only at intervals as needed, the expense for its maintenance is insignificant.

Referring to Fig. 1, the numeral 2 represents the shell or casing of the knob which may be of any suitable material say for example, brass, and it may be of any desired form such as cylindrical, oval or polygonal, either plain or ornamental as desired. As 80 here shown, the knob casing 2 is a cylindrical casting which extends in a left hand direction to form a boss 3 in which is secured a square stem or spindle 4 coacting in the usual manner with the door locking or 85 latching mechanism, the extension being conical for part of its length. Contained within this conical extension of the knob is a conical tube, 6, of glass or other transparent substance, and the walls of the extension 90 are in part cut away as shown at 7 in Fig. 2, so as to form openings through which light 95 may pass.

Inside of the knob casing 2 is an electrical battery preferably of the so called "dry" 100 type which may be constructed in any one of the well known ways and as here shown comprises an outer containing cylinder 11 of zinc which is insulated from the knob casing by the insulation 15. The interior of the 105 zinc cylinder is lined with cloth, blotting paper of other suitable absorbent material 12, and contains a block of carbon 13, the remaining space in the battery being filled with the combined electrolyte and depolarizer 110 14.

Inclosed within the glass tube, 6, and held

between the insulation 15 and the extension of the knob, is a reflector of metal or any suitable material, 21, which forms a socket for an incandescent lamp, 8, the base of which abuts a contact, 16, embedded in the screw cover, 17, and push button 22, and connection between the negative element or electrode of the battery and one terminal of the incandescent lamp 8. The return circuit for the lamp is established from the base of the lamp, through the screw socket 9, to the knob casing 2, hence through the screw cover 17, and push button 22, and contact 20, of the battery, the latter contact being secured to the zinc, 11, which forms the positive element or electrode of the battery. The contacts 22 and 20 are held normally in open position as shown by the spring 23, carried by the cover 17, and are brought into electrical contact, or rather the spring 23, is brought into electrical engagement with the contact 20, by a pressure on the button 22.

The cover 17 is here shown as being screwed to the knob casing 2 which arrangement is well adapted to a cylindrical knob, since it permits of easy removal, and when tightly screwed in place, bears against the insulation 15 and thus securely holds the battery against displacement and insures a firm electrical engagement between the center terminal of the lamp and button 16 as well as rendering the interior of the knob dust and moisture proof. Since the screw socket 9 is yieldable to a certain extent, the same acts in the nature of a spring, so as further to insure a good electrical contact between the lamp and button 16, and also automatically to compensate for any slight variation in the dimensions of different lamps or batteries as well as to allow for any expansion or contraction of the various parts.

In case the knob be of other shape than cylindrical, I may still retain the screwed cover by providing the knob casing with a circular screw threaded flange, or if the cover be of the same shape as the knob, say for example, square or polygonal, the same 50 may be pressed into place and secured by screws or other suitable means so as to permit of the cover being removed when necessary.

Fig. 3 represents a safe having the usual combination lock 29 and showing the embodiment of my invention as illustrated in Fig. 1 applied thereto; Fig. 4 shows the embodiment of my invention illustrated in Fig. 1 as being applied to a door lock 30 so as to enable one to light up the key hole 31.

An illuminating device containing an embodiment of my invention may be constructed at very little expense and, since the 65 interior space in the knob, which heretofore

was wasted, is utilized to contain the various parts, the knob does not have to be made any larger than one of standard size. The device is devoid of all complications and does not require any electric wiring, and 70 since all parts are inclosed, the device may be located in a position exposed to the weather without any danger of it becoming damaged or of having its efficiency impaired. If after long use, the lamp or battery should 75 become exhausted and need to be replaced, the cover of the knob can be easily and quickly removed without the use of tools of any kind and the battery and lamp may be lifted out. The batteries can be made up 80 in quantities at small expense and as the lamp is of standard size and can be purchased anywhere for a few cents, the entire cost of maintenance is but trifling.

If desired the batteries may be made 85 smaller so as to permit of using two or more in series to accommodate a lamp of higher voltage. This change could not involve any complications since the batteries would simply be placed or nested one on top of the 90 other within the knob.

From the foregoing description it will be seen that my device comprises a hollow door knob with an extension applied to the usual door latch spindle, said extension being prolonged and arranged for a lamp bulb with a reflector inclosed therein, and also a glass shield surrounding the lamp and reflector to protect the same from the elements. The extension of the knob is formed conically 95 with openings surrounding it so that the light from the lamp may be allowed to shine all around the knob. It will also be noticed that the peculiar shape of the reflector will throw the light out through said openings. As the door knob is limited in size it has been found necessary to utilize all the room in the knob, and to this end I have provided the battery as shown in the drawings. The battery having its contacts or terminals 100 in axial alinement, does away with the necessity of any skill in assembling the knob, as the battery will naturally take the proper position.

I desire not to be limited to the precise construction and arrangement of parts herein disclosed, since it is obvious that one skilled in the art could readily make various changes without departing from the spirit and scope of the invention. 115

What I claim is:—

1. A hollow knob adapted for manual operation, a battery in said hollow, a conical extension on the knob, an electric lamp in said extension surrounded by a conical glass shield, and openings in said extension for the light from said lamp to shine through in all directions circumferentially of the knob. 125

2. A hollow knob adapted for manual operation, a battery in said hollow, an exten- 130

sion on the knob, an electric lamp in the extension surrounded by a shield, openings in said extension, and a reflector back of said lamp shaped to throw the light from said lamp through said openings.

3. A hollow knob adapted for manual operation, a battery in said hollow, terminals in said battery in axial alinement with each other, an extension on the knob, an electric lamp in said extension surrounded by a shield, openings in said extension for the light from the lamp to shine through circumferentially of the knob, and means carried in the end of the knob to engage one terminal of the battery.

4. A hollow knob adapted for manual operation, a battery in said hollow, rigid terminals for said battery in axial alinement with each other, an extension on said knob, an electric lamp in said extension surrounded by a shield, and openings in said extension for the light from the lamp to shine through in all directions circumferentially of the knob.

5. A hollow knob adapted for manual operation, an extension on the knob, a cover for the knob, an illuminating device carried by the knob and extension, part of said illuminating device being carried in and wholly surrounded by said extension and part carried in and surrounded by the knob proper, a switch carried by said cover, and means associated with the cover for controlling said switch.

6. A hollow knob adapted for manual operation, an extension for the knob, a cover for the knob, an illuminating device comprising an incandescent lamp and a cell or dry battery, the lamp being carried by and wholly surrounded by the extension of the knob, and the cell or dry battery being carried by and wholly surrounded by the knob proper, a switch carried by said cover, and a push button in said cover for controlling a circuit between the said battery and lamp.

7. A hollow knob adapted for manual operation, an extension formed on the knob, an illuminating device comprising a battery and incandescent lamp, and a transparent shield surrounding the lamp, said lamp and shield being carried within said extension and said battery being carried within the knob proper.

8. A hollow knob adapted for manual operation, an extension formed on the knob, an electric bulb, a battery contained within the knob proper, a glass shield surrounding the said bulb, said bulb and shield being contained within and wholly surrounded by said extension, and openings in the periph-

ery of said extension to permit light from the bulb to pass through.

9. A hollow knob adapted for manual operation, an extension formed on the knob, an electric bulb, a battery contained within the knob proper, a glass shield surrounding the said bulb, said bulb and shield being contained within and wholly surrounded by said extension, openings in the periphery of said extension to permit light from the bulb to pass through, and a screw cover for the knob for retaining said battery, bulb and shield in fixed relation.

10. A hollow knob adapted for manual operation, an extension formed on the knob, an illuminating device comprising a battery and incandescent bulb, a shield of transparent material surrounding the bulb, and a reflector for the bulb, said bulb, reflector and transparent shield being carried by and wholly within said extension, and the battery being carried by and wholly within the knob proper.

11. A knob adapted for manual operation, an extension formed on the knob, an illuminating device comprising a battery and lamp, the lamp being carried within and surrounded wholly by said extension, the battery being carried by the knob proper, openings in said extension for permitting the light from the lamp to pass through, a conical glass shield surrounding the lamp and closing said openings, and a socket and reflector for the lamp formed integral and contained wholly within the extension of the knob, the reflector being substantially the shape of a frustum of a cone having its sides concave.

12. A knob adapted for manual operation, an illuminating device comprising an incandescent bulb, a reflector carrying said bulb, a transparent shield surrounding said bulb and reflector, an extension formed on the knob and surrounding said lamp, reflector and shield and provided with openings through which the light from the lamp may pass through, a battery carried within the knob proper, one terminal being in constant engagement with the lamp, a cover for said knob proper carrying a push button, a contact in engagement with said button and adapted to engage the other terminal of said battery when operated.

In testimony whereof, I have signed my name to this specification in the presence of two subscribing witnesses.

AUGUST SUNDH.
